UNITED STATES PATENT OFFICE.

JOSIAH W. KENNEDY, OF ST. LOUIS, MISSOURI.

FOUNDATION CONSTRUCTION.

SPECIFICATION forming part of Letters Patent No. 735,390, dated August 4, 1903.

Application filed March 16, 1903. Serial No. 147,936. (No model.)

To all whom it may concern:

Be it known that I, JOSIAH W. KENNEDY, a citizen of the United States, and a resident of the city of St. Louis, State of Missouri, have 5 invented a certain new and useful Foundation Construction, of which the following is a specification.

My invention relates to foundations for building and other structures, and has for its 10 principal object to secure an advantageous distribution of the stresses due to the weight of the superstructure.

It consists in the construction and in the arrangement of parts hereinafter described 15 and claimed.

In the accompanying drawings, which form part of this specification and wherein like symbols refer to like parts wherever they occur, Figure I is a plan view of a foundation 20 structure embodying my invention. Fig. II is a longitudinal section thereof. Fig. III is a cross-section thereof on the line III III of Fig. II. Fig. IV is a cross-section thereof on the line IV IV of Fig. II. Fig. V is an enlarged detail view of a vertical longitudinal 25 section of the end portion of a foundation structure. Fig. VI is a horizontal sectional detail of the end portion of a girder, and Fig. VII is a plan view of a series of foundation 30 structures arranged to constitute the foundation of a building.

My invention comprises an elongated pier or foundation structure consisting of metal members embedded in concrete and arranged 35 to support columns at its ends and intermediate thereof. Preparatory to building the foundation structure an elongated trench of the size and shape of the structure is dug in the ground. The end portions of the trench 40 are laterally extended on each side, and their bottoms are preferably horizontal. From these horizontal end portions the bottom of the trench inclines downwardly and reaches its greatest depth midway of the length of the 45 trench. In building the foundation structure the concrete in a plastic condition is filled in to the amount required to properly position the metal member or members and then more concrete is filled in to embed said 50 members and properly position others, &c.

Embedded in the concrete 1 in the widened end portions of the trench are series of rigid

bars or I-beams 2, arranged horizontally transversely of the main portion of the trench. Upon these transverse bars or I-beams rest 55 main girders or I-beams 3, which extend nearly the full length of the trench and are likewise embedded in the concrete. Upon the ends of the longitudinal girders are shoes 60 or broad plates 4, whose ends are bent around and bolted to the top and bottom of the girder, whereby said plates form mechanical bonds between their girders and the concrete. For the same purpose the girders have transverse projections arranged thereon near their 65 ends—such, for instance, as angle-irons 5, riveted thereon.

Metal tension-rods 6, extending under the transverse end beams, are anchored near the ends of the concrete, as by turning their ends 70 up and over the top of the inmost beams. These inmost bars are smaller or are set lower than the inner bars to allow for the portions of the shoes and of the tension-rods intervening between the tops of the outer bars and 75 the main girders, so that the main girders will have a firm bearing on the transverse bars. The middle portion of the main girders has a series of hangers or supporting-straps 7 suspended therefrom and the middle 80 portions of the tension-rods rest upon these hangers. These hangers are preferably made in the form of U-shaped straps whose ends are screw-threaded. These threaded ends 8 extend upwardly through a perforated bar 9, 85 resting on the girders, and are adjustably supported therefrom by nuts 10, working on said threaded ends. The hangers are so arranged that the middle portion of the tension-rods lie close to the under side of the girders 90 and the outer portion of said tension-rods inclines downwardly to the edge of the inmost transverse bars. The hangers thus tie the girders and the tension-rods together, whereby the middle portions of the girders are anchored against upward movement. 95

In practice each end of the foundation structure supports a column 11, and the superstructure is designed so that the principal weight is carried by these end columns. One 100 or more columns designed for lighter loads rest upon the middle or intermediate portion of the foundation structure. By this arrangement the weight of the superstructure pro-

duces tensile and compressive stresses which are variously distributed in different parts of the foundation structure. In the upper portion thereof the principal stress is tension, which is taken up in the main girders and by the tension-rods. In the lower portion of the structure the stress is principally compression and is taken up in the concrete. As the foundation structure is rigid, the weight of the superstructure resting on one end of the foundation structure tends to balance the weight on the other end thereof and the entire weight is distributed uniformly over an area of ground equal to the area of the horizontal section of the foundation structure.

Fig. VII illustrates a plan of a foundation for a building embodying my foundation structure. As shown in said figure, a series of foundation structures are arranged parallel with each other and with the columns supported on the ends thereof in proper alignment to carry the external walls of the building and with the intermediate columns arranged to carry an inside wall.

The principal advantages of my invention for the foundations of buildings are that it distributes the weight over a large area of ground and that the greater portion of the weight is carried toward the center of the building. In consequence of this last-mentioned fact an excavation at the side of the building may be made with comparatively little risk to the building and without necessitating the usual shoring. So, too, the foundation need not go as deep as has heretofore been necessary, and consequently there is a considerable saving in the cost of excavation therefor and in materials and labor.

What I claim is—

- 40 1. A foundation structure comprising one or more metal girders extending from wall to wall and resting at their ends on transversely arranged bars, all embedded in concrete.
2. A foundation structure comprising one or more metal girders resting at their ends upon transversely-arranged bars, and tension-rods, all embedded in concrete.
3. A foundation structure comprising one or more metal girders resting at their ends upon transversely-arranged bars, and tension-rods whose middle portions are close to the under side of the girders, all embedded in concrete.
4. A foundation structure comprising one or more metal girders resting at their ends upon transversely-arranged bars, and tension-rods whose middle portions are close to the under side of the girders and whose end portions extend under said transverse bars, all embedded in concrete.
5. A foundation structure comprising one or more metal girders resting at their ends upon transversely-arranged bars, and tension-rods whose middle portions are tied to the middle portions of the girders and whose end portions extend under said transverse bars, all embedded in concrete.

6. A foundation structure comprising one or more metal girders resting at their ends upon transversely-arranged bars, and tension-rods whose middle portions are close to the under side of the girders and whose end portions extend under said transverse bars and are anchored thereto, all embedded in concrete.

7. A foundation structure comprising one or more metal girders resting at their ends upon transversely-arranged bars, and tension-rods whose middle portions are tied to the middle portions of the girders and whose end portions extend under said transverse bars and are anchored thereto, all embedded in concrete.

8. A foundation structure comprising one or more metal girders resting at their ends on transversely-arranged bars, all embedded in concrete, the depth of the concrete increasing toward the middle of the girders.

9. A foundation structure comprising one or more metal girders resting at their ends upon transversely-arranged bars, and tension-rods arranged close below the middle portions of said girders, all embedded in concrete, the depth of the concrete increasing toward the middle of the girders.

10. A foundation structure comprising one or more metal girders resting at their ends upon transversely-arranged bars, and tension-rods arranged close below the middle portions of said girders and tied thereto, all embedded in concrete, the depth of the concrete increasing toward the middle of the girders.

11. A foundation structure comprising one or more metal girders resting at their ends on transversely-arranged bars, the ends of said girders having plates secured transversely thereto, all embedded in concrete.

12. A foundation structure comprising one or more metal girders resting at their ends on transversely-arranged bars, the ends of said girders having plates secured transversely thereto and said girders having lateral projections near their end portions, all embedded in concrete.

13. A series of parallel foundation structures each comprising one or more metal girders resting at their ends on transversely-arranged bars, all embedded in concrete, columns supported at the ends of each of said structures and midway between said ends, and a superstructure supported on said columns.

14. A series of parallel foundation structures each comprising one or more metal girders resting at their ends upon transversely-arranged bars, and tension-rods arranged under the middle portions of the girders and close thereto, all embedded in concrete, columns supported at the ends of each of said structures and midway between said ends, and a superstructure supported on said columns.

15. A series of foundation structures each comprising one or more metal girders resting

- at their ends upon transversely - arranged bars, and tension-rods whose middle portions are close to the under side of the girders and whose end portions extend under said transverse beams and are anchored, all embedded in concrete; columns supported at the ends of said structures and midway between said ends, and a superstructure supported on said columns.
16. A series of foundation structures each comprising one or more metal girders resting at their ends upon transversely - arranged bars, and tension-rods whose middle portions are close to the under side of the girders and tied thereto and whose end portions extend under said transverse beams and are an-

chored, all embedded in concrete, columns supported at the ends of said structures and midway between said ends, and a superstructure supported on said columns.

17. In a building, the combination of a series of parallel foundation structures each comprising one or more metal girders resting at their ends on transversely-arranged bars, all embedded in concrete, and a superstructure supported on the ends of said foundation structures, substantially as described.

JOSIAH W. KENNEDY.
